UNITED STATES PATENT OFFICE.

WILLIAM M. ELIAS, OF NEW YORK, N. Y.

DESIGN FOR MEDAL-BATTERIES.

Specification forming part of Design No. 11,463, dated October 21, 1879; application filed September 25, 1879.
[Term of patent 3½ years.]

To all whom it may concern:

Be it known that I, WILLIAM M. ELIAS, of New York, in the county of New York and State of New York, have originated a new Design for Electro-Medical Batteries; and I do hereby declare that the following is a full, clear, and exact description thereof, reference being had to the accompanying drawings, and to the letters of reference marked thereon, which form part of this specification.

A represents a central scalloped hub, from which radiate or extend the spokes d d. b represents the circular rim, and c e the crescent-shaped connections which unite the spokes, and which also are connected with the outer rim, b, thus forming the open spaces g g between the crescents and rim, and between the hub and crescents, as fully illustrated by the accompanying drawing.

The hub, or indeed the whole metallic face of the device, may be ornamented with any kind of figure or figures that may be selected.

What I claim as my invention is—

A design for electro-medical batteries, consisting of a central scalloped hub having radiating spokes which are surrounded by an outer rim, and between which are crescent connections, all substantially as herein shown and described.

In testimony that I claim the foregoing as my own I affix my signature in presence of two witnesses.

WM. M. ELIAS.

Witnesses:

ARTHUR L. BISHOP,
EDWARD K. YOUNG.
